CLAIM

The ornamental design for a ventilation louver as shown and described.

DESCRIPTION

FIG. 1 is a front perspective view of a ventilation louver showing the new design.

FIG. 2 is a rear perspective view of the ventilation louver showing the new design.

FIG. 3 is a front elevational view thereof.

FIG. 4 is a rear elevational thereof.

FIG. 5 is a top plan view thereof.

FIG. 6 is a bottom plan view thereof.

FIG. 7 is a right side elevational view thereof; and,

FIG. 8 is a left side elevational view thereof.

The broken lines in the drawings depict portions of the ventilation louver that form no part of the claimed design. The ventilation louver includes symbolic break lines along its height. The break lines, brackets, and the area between the break lines form no part of the claimed design.
